(57) CLAIM

The ornamental design for a jewel display box, as shown and described.

DESCRIPTION

FIG. 1 is a front perspective view of a jewel display box showing my new design.

FIG. 2 is a rear perspective view thereof.

FIG. 3 is a front view thereof.

FIG. 4 is a rear view thereof.

FIG. 5 is a left and right end view thereof.

FIG. 6 is a top and bottom view thereof.

FIG. 7 is an exploded view thereof.

FIG. 8 is an alternative front perspective view thereof.

FIG. 9 is an alternative rear perspective view thereof; and,

FIG. 10 is an alternative exploded view thereof, wherein the broken lines shown in the drawings are for illustrative purposes only and form no part of the claim.
